UNITED STATES PATENT OFFICE.

WILLIAM BERRY, OF FOND DU LAC, WISCONSIN, ASSIGNOR OF ONE-HALF TO GEORGE W. POST, OF FOND DU LAC, WISCONSIN.

RAIL-CLAMP.

No. 928,020.

Specification of Letters Patent.

Patented July 13, 1909.

Application filed April 3, 1909. Serial No. 487,751.

To all whom it may concern:

Be it known that I, WILLIAM BERRY, a citizen of the United States, residing at Fond du Lac, in the county of Fond du Lac and State of Wisconsin, have invented certain new and useful Improvements in Rail-Clamps; and I do hereby declare the following to be a full, clear, and exact description of the invention, such as will enable others skilled in the art to which it appertains to make and use the same.

My invention relates to rail clamps of the class which do not take the place of the ordinary spikes for securing the rails to the ties but which serve as safety devices to prevent the rails from moving or creeping upon the ties.

The object of the invention is to provide a clamp of this kind which is simple and cheap of construction and which may be quickly adjusted and secured to the rail or released and removed therefrom.

Other objects of the invention will become apparent from the following description.

The invention consists primarily of a clamp comprising a portion extending below the rail, a hook on the end of said portion adapted to engage one side of the foot of the rail, and a resilient jaw on the other end of said portion for gripping the other side of the foot of the rail.

The invention also consists in the features of construction and combinations of parts hereinafter described and specified in the claims.

In the accompanying drawing illustrating the preferred embodiment of my invention: Figure 1 is a plan view of parts of two ties and one rail, showing one of my improved rail clamps in operative position. Fig. 2 is a sectional view on the line x—x of Fig. 1, and Fig. 3 is a detailed view of the clamp alone.

The clamp 1 is arranged at the side of the tie 2 and holds the rail 3 against lateral movement thereon. Said clamp is preferably made in one strip of malleable metal bent to form a portion 4 extending below the rail, a hook 5 on one end of said portion adapted to engage one side of the foot of the rail and a resilient jaw 6 on the other end of said portion adapted to grip the other side of the foot of the rail. Said resilient jaw is

formed by extending the portion 4 beyond the rail and bending it back upon itself, an open eye or loop 7 being formed at the bend 55 whereby greater resiliency is obtained in the jaw and means also provided for securing the clamp to the side of the tie.

While any form of spike or bolt may be employed for fastening the clamp to the tie, I 60 prefer to use a staple 8, as shown, as it holds more firmly and allows the clamp to move thereon without tending to loosen said staple from the tie. One prong of the staple is passed through the eye or loop 7. A bolt 9 65 carrying a nut 10 comprises the means preferably employed for drawing down and holding the jaw so as to grip the foot of the rail. A simple form of nut lock comprising a bent piece of metal 11 is illustrated for preventing 70 the nut from becoming loose.

It will be understood that any form of nut lock or means for holding the jaw upon the foot of the rail may be employed without departing from the spirit or sacrificing the advantages of my invention. 75

I claim:

1. The combination, with a rail and a tie, of a rail-clamp arranged at the side of the tie and comprising a portion extending below 80 the rail, a hook on one end of said portion for engaging one side of the foot of said rail, the other end of said under portion being bent upon itself forming an open loop at its extremity and a resilient jaw to grip the other 85 side of the foot of the rail, means passed through said loop for securing said clamp to the side of the tie, and means to hold said jaw down upon the foot of the rail.

2. The combination, with a rail and a tie, 90 of a rail-clamp arranged at the side of the tie and comprising a portion extending below the rail, a hook on one end of said portion for engaging one side of the foot of said rail, the other end of said under portion being bent 95 upon itself forming an open loop at its extremity and a resilient jaw to grip the other side of the foot of the rail, a staple passed through said loop and into the side of the tie, and means to hold said jaw down upon the 100 foot of the rail.

3. The combination, with a rail and a tie, of a rail-clamp arranged at the side of the tie and made of a single strip of malleable metal

bent to form a portion extending below the rail, a hook on one end of said portion for engaging one side of the foot of the rail, and a resilient jaw to grip the other side of the foot of the rail, means to hold said jaw down upon the foot of the rail, and means to secure said clamp to the side of the tie.

In testimony whereof, I affix my signature, in presence of two witnesses.

WILLIAM BERRY.
